SUPERHEATER BOILER

Filed Nov. 24, 1925

UNITED STATES PATENT OFFICE.

JOHN PRENTICE, OF BAYONNE, NEW JERSEY, ASSIGNOR TO THE BABCOCK AND WILCOX COMPANY, OF BAYONNE, NEW JERSEY, A CORPORATION OF NEW JERSEY.

SUPERHEATER BOILER.

Application filed November 24, 1925. Serial No. 71,043.

My present invention relates to superheater boilers in which a superheater is positioned between banks of water tubes, and will be best understood from the following description and the annexed drawings in which Fig. 1 is a sectional side elevation of a part of a water tube boiler of a well-known form with a superheater embodying my invention; Fig. 2 is an enlarged view of the ends of one of the headers shown in Fig. 1, and Fig. 3 is a perspective looking in the direction of the arrows 3-3 in Fig. 1.

Like references indicate like parts throughout the drawings.

In the illustrative arrangement, the boiler has a lower bank 10 of horizontally inclined water tubes and an upper bank 11 of water tubes, these banks being connected to uptake headers 12 and downtime headers 13 in the usual manner. The banks 10 and 11 are spaced apart to provide a superheater chamber and in this chamber is a U-tube superheater having an inlet header 14 and an outlet header 15 extending across the space and through the side walls of the boiler setting, the headers 14 and 15 being connected by superheater tubes 16 extending longitudinally of the water tubes.

The header 15 is supported on supporting members 17 resting on the tubes 10 and with the lower ends of their feet in contact with the headers 13, so that the horizontal thrust of the header 15 will be carried to the headers 13. The header 14 is provided with a fin 18 which is attached to the lower ends of baffle plates 19, 20, each extending through an oblique aisle in the bank 11 and with recesses in its edge surrounding the tubes of the bank 11 so as to be supported thereby. As will be best seen in Fig. 3, the weight of the superheater header 14 is thus transmitted to the water tubes of the bank 11.

On the tubes of the bank 10 are piers or columns of refractory material 21 each resting on a plate 22 held against longitudinal movement by a tube clamp 23, the refractory 21 being covered by a plate 24 on which rests the lowermost row of the tubes 16. The several rows of the tubes 16 may be connected by plates 25 to maintain the several rows of tubes in proper relation, the upper portion of the tubes 16 also being provided with similar plates 26.

Between the headers 14 and 15 is a suspended baffle made up of a series of plates

27 connected at the tops and bottoms respectively to fins on the headers 14 and 15, the inner face of the members 27 being covered with tile 28 connected to the plates 27 by bulb members in the well-known manner.

It has heretofore been proposed to suspend the superheater located between banks of water tubes entirely from the boiler parts, in order to permit the superheater to be movable with the boiler parts without producing any undue strain on the suspension members or on the superheater parts. Such an arrangement is satisfactory, but I have found that in some cases, the weight of the steam pipes connected to the outer ends of the headers is so great as to produce an undue amount of strain on the suspension members connected to the boiler parts. To overcome this difficulty, I provide at such points an additional support from some fixed member, as, for instance, a beam in or adjacent the side wall, but, in order not to obviate the advantages of having the superheater suspended so as to move with the boiler, I make such support a yielding resilient one, so that, while such additional point of support may be provided, nevertheless the superheater headers will still be free to move with the boiler.

In the illustrative embodiment, the setting side wall 29 has an enlarged opening 30 through the walls thereof through which the end of the header 14 extends. A fixed beam 31 outside of the wall 29 has thereon a pair of supports 32 covered by a channel section 30 cover plate 33 through which extends the ends of a U-shaped hanger 34, the upper ends of the hanger being provided with adjusting nuts 35 and washers 36, the latter resting on coiled springs 37, the lower ends of which rest against the cover plate 33. With the arrangement provided, it will be obvious that by adjusting the nuts 35, the springs 37 may be tensioned to give any desired amount of support to the header 14 and yet if the header 14 tends to move up or down with the boiler parts, it may do so by reason of the yielding, resilient character of the spring suspension which I provide.

The holes in the cover plate 33 through which the ends of the hanger 34 extend may be made large enough to permit the header 14 to move horizontally when the boiler parts, from which that header is suspended, move horizontally.

It will be understood that the arrangement shown in Fig. 2 may be applied also to the outlet header 15 and may also be provided at the opposite ends of the headers. 5 Ordinarily, however, where the piping can be arranged so as to be substantially self-supporting and yet yielding enough to permit movement of the header 15, the spring suspension is not necessary. For that reason, 10 in the form shown, such spring suspension is shown only for the inlet header 14 and not for the outlet header 15.

It will be understood that the arrangement which I have shown is merely illustrative and that the embodiment of my invention may be widely varied. For instance, 15 it may be applied to any boiler having divided banks of tubes in which a superheater is located and it may be applied to such superheaters irrespective of whether the tubes are longitudinal or crosswise of the water tubes.

I claim:

1. A steam boiler having banks of water tubes connected to water chambers with a space between the banks, a tubular superheater having a tubular heating surface in said space, and supports for the superheater, 25 some of said supports being connected to the boiler and others of said supports being connected resiliently to the boiler setting.
2. A steam boiler having banks of water tubes connected to water chambers with a space between the banks, a superheater having inlet and outlet headers connected by tubes, with at least a portion of the tubes in said space, a fixed member, resilient supports between the fixed member and the superheater, and fixed connections between the 35 superheater and the boiler.
3. A steam boiler having banks of water tubes connected to water chambers with a space between the banks, a superheater having inlet and outlet headers connected by tubes, with at least a portion of the tubes in said space, a fixed member, resilient supports between the fixed member and the superheater headers, and fixed supports between the boiler and the superheater tubes. 45
4. A steam boiler having banks of water tubes connected to water chambers with a space between the banks, a superheater having inlet and outlet headers connected by tubes, with at least a portion of the tubes in said space, a fixed member, yielding supports between the fixed member and the superheater headers, fixed supports between the headers and the boiler, and other fixed supports between the superheater tubes and 55 the boiler.
5. In a steam boiler, an upper and a lower bank of horizontally inclined water tubes spaced apart, a superheater having an inlet and an outlet header extending through said space at right angles to the boiler tubes, 60

tubes within said space and connecting said headers, a fixed member at one end of one of said headers, and a yielding member between said end and said fixed member to support said end at least in part. 70

6. In a steam boiler, an upper and a lower bank of horizontally inclined water tubes spaced apart, a superheater having an inlet and an outlet header extending through said space at right angles to the boiler tubes, 75 tubes within said space and connecting said headers, a fixed member at the outlet end of said outlet header, and a yielding member between said end and said fixed member to support at least in part said end and the piping connected thereto. 80

7. In a steam boiler, an upper and a lower bank of horizontally inclined water tubes spaced apart, a superheater having an inlet and an outlet header extending through said space at right angles to the boiler tubes, 85 tubes within said space and connecting said headers, a fixed beam outside the boiler setting at one end of one of said headers, and springs between said beam and said end to transmit at least some of the weight of said end and the piping connected thereto to said beam. 90

8. In a steam boiler, an upper and a lower bank of horizontally inclined water tubes 95 spaced apart, a superheater having an inlet and an outlet header extending through said space at right angles to the boiler tubes, tubes within said space and connecting said headers, a fixed member outside the boiler 100 setting and above an end of one of said headers, a U-shaped hanger around said end with the legs of the U extending through said fixed member, a spring around each leg above said fixed member, and means on each leg to bear against the end of the spring. 105

9. In a steam boiler, an upper and a lower bank of horizontally inclined water tubes spaced apart, a superheater having an inlet and an outlet header extending through said 110 space at right angles to the boiler tubes, tubes within said space and connecting said headers, a fixed member outside the boiler setting and above an end of one of said headers, a U-shaped hanger around said end with the legs of the U extending through said fixed member, a spring around each leg above said fixed member, and means on each leg to bear against the end of the spring, 115 said means including a nut, whereby the tension of the spring may be adjusted. 120

10. In a steam boiler, an upper and a lower bank of horizontally inclined water tubes spaced apart, a superheater having an inlet and an outlet header extending through said space at right angles to the boiler tubes, 125 tubes within said space and connecting said headers, supports between said headers and the banks of water tubes, whereby the greater part of the weight of the superheater 130

- is carried on said water tubes, a fixed member at one end of one of said headers, and a yielding member between said fixed member and said end to support said end at least in part. 5
11. In a steam boiler, an upper and a lower bank of horizontally inclined water tubes spaced apart, a superheater having an inlet and an outlet header extending through said space at right angles to the boiler tubes, tubes within said space and connecting said headers, one of said headers being at a level higher than the level of the other of said headers, supports between the lower header and the lower bank of water tubes, suspension devices between the upper bank of water tubes and the upper header, a fixed member at one end of one of said headers, and a yielding member between said fixed member and said end to support said end at least in part. 10
12. In a steam boiler, an upper and a lower bank of horizontally inclined water tubes spaced apart, a superheater having an inlet and an outlet header extending through said space at right angles to the boiler tubes, one of said headers being at right angles to the boiler tubes, one of said headers being at a level higher than the level of the other header, U-tubes in said space and extending in the same general direction as the water tubes and connecting said headers, supports between the lower header and the lower bank of water tubes and holding said lower header in substantially fixed relation to said lower bank, suspension devices between the upper bank and the upper header and holding said upper header in substantially fixed relation to said upper bank, a fixed member adjacent one end of one of said headers, and a yield- 15 20 25 30 35 40
- ing member between said end and said fixed member arranged to support said end at least in part and to permit movement thereof relatively to said fixed member. 45
13. In a steam boiler and its setting, a superheater, means associated with boiler parts for supporting said superheater in substantially fixed relation thereto, and other means associated with the setting for supporting said superheater in resilient relation to said setting. 50
14. In a steam boiler and its setting, said boiler comprising water tubes, a superheater comprising a header an end of which extends through an opening in the setting, a fixed member located outside of the setting, means for supporting the superheater from said boiler tubes, and means for yieldingly supporting the end of said header by said fixed member. 55 60
15. In a steam boiler and its setting, said boiler comprising water tubes, a superheater comprising headers connected by superheater tubes, means for supporting both the headers and the tubes of the superheater from the boiler tubes, the headers of the superheater extending through openings in the setting, fixed members located outside of the setting, and means for yieldingly supporting the ends of said headers by said fixed members. 65 70
16. In a steam boiler comprising water tubes and its setting, a superheater, means connected to boiler tubes for supporting said superheater at certain points in substantially fixed relation to the tubes, and other means for supporting said superheater at another point in resilient relation to said setting. 75

JOHN PRENTICE.
